UNITED STATES PATENT OFFICE.

EDWARD BOWMAN, OF DUBUQUE, IOWA.

ADJUSTABLE VENTILATOR-HOOD FOR AUTOMOBILES.

1,387,584.

Specification of Letters Patent. Patented Aug. 16, 1921.

Application filed October 27, 1919. Serial No. 333,543.

To all whom it may concern:

Be it known that I, EDWARD BOWMAN, a citizen of the United States, residing at Dubuque, in the county of Dubuque and

5 State of Iowa, have invented a certain new and useful Improvement in Adjustable Ventilator-Hoods for Automobiles, of which the following is a specification.

This invention relates to hoods for winter 10 use over the radiator fronts of automobiles to adjustably regulate the amount of cold air admitted. The object of the invention is to provide a mechanism of this class which is readily applicable to and removable from 15 position and which contains doors or shutters adjustable from the seat of the automobile to control the amount of air admitted to the engine. This seat control is desirable because of the well known fact 20 that as the engine heats up while running it will stand a great deal more cold air than when it is cold at starting, and it is obviously inconvenient for the operator of the automobile to get out of his seat, perhaps in 25 the rain and mud, to go to the front of the car to vary the hood opening as has heretofore been necessary.

The invention consists in mechanism for carrying out the foregoing objects, which 30 can be easily and cheaply made, which is neat and compact in form, satisfactory in operation, and is not readily liable to get out of order. More particularly, the invention consists in many features and details of 35 construction hereinafter more fully set forth in the specification and claims.

Referring to the drawings in which like numerals represent similar parts throughout the several views,

40 Fig. 1 is a perspective view of a metallic frame and operating parts connected therewith, upon which the imperforate cloth forming a hood proper is built to make the complete device of this invention.

45 Fig. 2 is a front elevation of the radiator of an automobile of well known construction having a hood of this invention applied thereto the doors or slats being shown in closed position.

50 Fig. 3 is a side elevation taken from the right hand side of Fig. 2 showing a rope operating mechanism leading away to the automobile seat, the air doors or slats being arranged for simultaneous operation.

55 Fig. 4 is the same view as Fig. 3 but with certain mechanism in changed position so

that only one of the doors is operated by the mechanism, said door being shown in open position.

Fig. 5 is a sectional detail view through 60 the center of the hood of Fig. 3, removed from the automobile, the air doors both being open.

Fig. 6 is a perspective view of the inside of the hood removed from the automobile, 65 the air doors being in the position of Fig. 5.

Fig. 7 is a plan view of the front of the automobile showing the method of securing the hood of this invention thereto.

Fig. 8 is a side view of an alternative operating mechanism in which a push and pull lever is used instead of the rope of Figs. 3 and 4.

In constructing the mechanism of this invention a metallic frame of the type shown 75 in perspective in Fig. 1 is provided comprising top and bottom members 10, end members 12, and such intervening members 14 parallel to members 10 as may be required to leave the desired air passage openings 16 80 in the frame. The particular frame here shown is provided with two such openings and therefore has only one such dividing member 14. On the side members 12 near the top of each opening 16 is provided some 85 sort of a pivot bearing 18, the same in the particular case here illustrated taking the form of circular eyelets through which the wire door frames 20 and 22 respectively pass and take pivotal bearings. These two door 90 frames 20 and 22 are of U-shaped form conforming in general to three sides of the opening 16, heretofore referred to, and one extremity of each of these members 20 and 22 is provided with a short shaft end 24 95 adapted to pass through an adjacent eyelet 18, as shown. These members 20 and 22 are made of spring material so that by compressing the free arm carrying this short member 24 a given door frame may be disengaged from the adjacent bearing or eyelet 18 for the purpose of being slipped into a pocket formed in the covering material which makes the frame into a complete door, as more fully appears hereafter.

100 The opposite end of each end door frame member 20 and 22 has extending from it beyond the adjacent bearing 18 a horizontal shaft 26, each inclosed with a spring 27 arranged to tend to hold the adjacent door 110 closed. From each shaft extends a crank arm 28. These crank arms are in fact iden-

tical in construction but for convenience the crank arm of door frame 20 is numbered 28 and that of door frame 22 is designated as 30. In the particular form of the device here illustrated crank arm 28 carries a crank arm 29 pivoted in the upper end of a vertically reciprocatable bar 32, cotter pin 34 holding the parts together. If it is desired to operate lower door 16 only while the upper door is closed this may be accomplished by merely removing cotter pin 34 and then removing crank pin 29 from bar 32. On the other hand the construction now to be described makes it possible to leave lower door 16 closed while the upper door is operated. The construction is:—

Crank arm 30 is provided with crank pin 36 which extends into an elongated slot 38 in the bar 32. Pivoted to the bar 32, below slot 38, by any suitable means as on stud 40 is a latch member 42 provided with a notch 44, the whole so arranged that when the parts are in position of Fig. 4 the bar 32 can reciprocate up and down past crank pin 36 without affecting crank arm 30 and its attached mechanism 22; but on the other hand, when latch 42 is swung to the position of Fig. 1, the crank arm 36 is rigidly attached to the bar and movement of the bar moves the crank arms 28 and 30 and consequently the members 20 and 22 in unison between the positions of Figs. 3 and 5.

Having provided the mechanism thus far described, the frame 10—12—14 is covered with suitable cloth material, such as a combination of felt 46 on the inside and oil-cloth 48 on the outside, attached thereto by suitable means such as stitching 50, the same arranged so as to leave the perforations 16 clear and open and to provide suitably shaped and arranged rearwardly extending side walls 52, horizontal top wall 54, adapted to embrace respectively the sides and top of the radiator front and be detachably secured thereto by inwardly turned metallic clips 56, bent as shown in Fig. 7. The imperforate hood material thus described is also made to form a bottom flap 58, detachably securable around the underside of the radiator by corresponding metallic clips 60. The hood top member 54 is provided with a perforation 62 arranged to allow the device to slip over the radiator cap 63 of conventional construction.

55 Stitched across the hood cover device just described in the lines 64 and 66 above the openings 16 are cover members for the door frames 20 and 22, the same being made in the form of pockets consisting of outside members 68 connected with inside members 70. These pocket shaped door covers 68—70 are arranged to inclose and cover the wire door frames 20 and 22 described, the inside members 70 being of such a length and terminating in the line 72 so that when either

frame 20 or 22, is so sprung that its shaft 24 is released from its pivot 18, the frame can be swung about its pivot 18 adjacent to shaft 26 to remove the frame from the pocket cover. The process of inserting the 70 door frame in the pocket is a reversal of that just described. This construction avoids the necessity of stitching the cover members 68 and 70 entirely about the component parts of the door 20 and 22. 75

The device of this invention in the form shown in Figs. 5 and 6 is sold as an article of commerce, applicable to any automobile (the sizes and shapes of course being varied to conform to the sizes of different makes of 80 automobiles). The operator on purchasing the device applies it to the radiator end of the automobile using the clips 56 and 60 to attach it in place. Having done this, in one form of construction he attaches the pulley 85 74 to the automobile frame 75 and passes over it a rope 76 attached at one end 78 to the rod 32, the other end 80 leading away to the seat occupied by the driver of the automobile. In the alternative construction 90 he mounts on the frame 75 of the automobile a pivot mechanism 82 for any suitable lever mechanism 84 attached to the rod 32 by suitable link connection 86 and connected by a push and pull rod 88 to the seat not shown 95 of the automobile.

Under this latter construction the operator seated in the automobile pushes or pulls the rod 88 to open and close the air door mechanisms of the hood of this invention. In the construction of Fig. 3 the operator pulls on rope 80 to open the doors and allows them to close by gravity due to the weight of the wire frames 20 or 22 and the covering pockets 68—70 with or without the 105 assistance of springs 27.

In very cold weather the operator moves latch 42 to the position of Fig. 4 and manipulates only one of the doors. In warmer weather he puts the latch in the position of 110 Figs. 1 and 3 and manipulates both doors. By regulating the distance he moves lever 88 or rope 80, he varies the amount of opening of one or both doors as the case may be, and thus has entire control of the amount of 115 air admitted to the radiator.

Having thus described my invention what I claim as new and desire to secure by Letters Patent, is:

1. In mechanism of the class described, in combination with an automobile having a radiator intake requiring regulation, a hood of flexible imperforate material detachably securable over the radiator, a plurality of air intake doors in said hood made of the same 125 material as the hood and connected directly thereto movable between two positions to exclude and admit air to the automobile radiator, means operable by the automobile driver on the seat for manipulating said 130

doors in the ventilator hood, and means for selectively varying the number of doors manipulated by said operating means.

2. In mechanism of the class described, a frame having a perforation therein, a hood of imperforate material secured above said frame, means for detachably securing said imperforate material to adjacent parts of an automobile radiator, a door frame member

10 pivotally mounted on said first mentioned frame member, and a pocket of imperforate material inclosing said frame member and secured to said first mentioned hood member, for the purposes set forth.

15 3. In mechanism of the class described, a supporting frame having a perforation therein, a hood of imperforate material bordering said frame and detachably securable in place, a door covering for the perforation in said frame, made in the form of a pocket whose outside is attached to and continuous with the first mentioned imperforate material, and a wire supporting frame inside said pocket pivotally connected to said frame, for the purposes set forth.

20 4. In mechanism of the class described, a supporting frame having a perforation therein, a hood of imperforate material bordering said frame and detachably securable in place, a door covering for the perforations in said frame, made in the form of a pocket whose outside is attached to the first mentioned imperforate material, and a wire supporting frame inside said pocket pivoted 25 to two opposite sides thereof, one of said pivotal connections being detachable for the purpose of inserting the wire frame in and removing it from said pocket frame member.

25 5. In mechanism of the class described, 40 a main frame, a plurality of door frame mechanisms pivoted on the main frame, a reciprocating bar in pivotal connection with one of said door frame mechanisms so that

reciprocating the bar operates that particular door frame, a pin and slot connection between said bar, and another of the door frame mechanisms whereby the bar may reciprocate without removing said door frame, and means for detachably rigidly connecting the second door frame mechanism to the bar.

45 6. In mechanism of the class described, a main frame, a plurality of door frame mechanisms pivoted on the main frame, a reciprocating bar in pivotal connection with one of said door frame mechanisms so that reciprocating the bar operates that particular door frame, a pin and slot connection between said bar and another of the door frame mechanisms whereby the bar may reciprocate without removing said door frame, and a latch member on the bar movable to two positions, in one of which it locks the bar to the second door frame mechanism and in the other of which it leaves it released.

50 7. In mechanism of the class described, a main frame, a plurality of door frame mechanisms pivoted on the main frame, a reciprocating bar in pivotal connection with one of said door frame mechanisms so that reciprocating the bar operates that particular door frame, a pin and slot connection between said bar and another of the door frame mechanisms whereby the bar may reciprocate without moving said door frame, and a pivoted 55 latch member on the bar movable to two positions, in one of which it locks the bar to the second door frame mechanism and in the other of which it leaves it released.

60 In witness whereof, I have hereunto subscribed my name in the presence of two witnesses.

EDWARD BOWMAN.
